UNITED STATES PATENT OFFICE.

HERBERT B. STEELE, OF BOSTON, MASSACHUSETTS.

GAS-IGNITER.

1,096,276.

Specification of Letters Patent. Patented May 12, 1914.

Application filed May 10, 1912. Serial No. 696,532.

To all whom it may concern:

Be it known that I, HERBERT B. STEELE, of Boston, in the county of Suffolk and State of Massachusetts, a citizen of the 5 United States, have invented a new and useful Improvement in Gas-Igniters, of which the following is a specification.

My invention comprises an electrically ignited burner especially adapted for igniting 10 acetylene gas for automobile lights although it may be used for other purposes.

Heretofore when a short length of electrically heated resistance wire has been used to light gas the life of the wire has been unsatisfactory due to the combined effects of 15 the gas and the electric current at the moment of ignition while both are turned on. I have found by experiment that the life of the resistance wire is increased as the quantity of current necessary to raise the resistance wire to the point of ignition is reduced although the temperature to which the resistance wire must be raised remains the same.

25 My invention comprises the use of a resistance so shaped that a great deal of the heat radiation from one part of the resistance is taken up by other parts by which the quantity of current required is materially 30 reduced and in its preferred form it comprises a fine coil of platinum or other wire in the circuit and preferably located within a suitable recess in the burner shaped for its reception. It also consists in the peculiar 35 means shown for holding a resistance in the path of the gas.

My invention in its preferred form will be understood by reference to the drawings, in which—

40 Figure 1 is a front elevation of a burner embodying my invention. Fig. 2 is a vertical section through the jet-piece carrying the resistance. Fig. 3 is a side elevation of said jet-piece. Fig. 4 is an elevation looking 45 into the jet-piece, Figs. 2, 3 and 4 being fractional portions of the burner, and Figs. 5 and 6 are details of the clips referred to below.

A is the metallic standard of the burner 50 from the upper end of which project the usual jet-pieces B and C. These are customarily made in one piece of lava or the like. I have provided each jet piece with a cup-shaped recess about its gas orifice.

55 The cavity of the jet-piece B is shown at 3

in Fig. 2, b^1 being the gas passage and b^2 , c^2 being air passages of which there are usually four. Within the cavity b is a platinum coil D which is connected at one end with a clip E and at the other end with a clip F. I prefer that these clips shall be constructed as follows. The clip E comprises arms e which clasp the jet-piece B and a finger e^1 which reaches up over the top of the jet piece and is there connected through the top passage b^2 with one end of the platinum D. The clip E also has a loop e^2 to which an electrical connection may be made with the battery. This clip is insulated from the standard A by the lava of which the tip is composed. The clip F has a central portion f which rests in the cavity or recess between the two jet-pieces. From this central portion f project downward two arms f^1 which engage the upper part 75 of the standard A to which they are soldered so as to make electrical connection therewith. It also has two upwardly-projecting arms f^2 , f^3 which extend up the walls of the recess in the inner air passages b^2 , c^2 and to one of which f^2 the other end of the coil D is attached. The coil D is made preferably 80 of very fine platinum wire coiled tightly so that the coils are in close proximity but not in contact. This is an important feature of 85 my invention, viz: that the coils shall be so near that a large part of the heat radiated from each coil will be taken up by the other coils rather than wasted. It will be readily understood that a straight piece of wire 90 when heated will radiate heat radially and the heat will dissipate, while in the case of a coil the rays of heat will intermingle, a large proportion acting and reacting upon the coil itself. Thus a much less amount of 95 current will give the necessary heat to the coil for ignition purposes than in the case of the straight piece of platinum, and the life of the coil will be much longer.

In utilizing my ignition device when embodied as shown the electric circuit is completed from one end of the coil D through the clip E, its loop e^2 , the connecting wire, circuit closer, battery and suitable connection to the standard A and clip F, and by 100 closing the circuit the coil will be heated, and the gas being turned on, will light the gas, after which the circuit will be broken. As stated above, much less current will be 105 needed with a device having a platinum coil 110

than with an igniter in which no coil is used and the deterioration of the igniter will be much less rapid.

I do not mean to limit myself to the precise mode of mounting the coil shown. Moreover the mode of mounting will be equally applicable to igniters in which a straight piece of platinum or other resistance wire is used.

10 I have referred to my resistance as being made of platinum, but I do not mean to limit myself to a coil of that metal as other metals may be used for the purpose although so far as I know platinum is the best.

15 The recess about the gas orifice I have found very desirable when used without my igniter as well as when used with it, for it forms in connection with the air passages a good mixing chamber. Moreover my invention may be applied to other kinds of 20 burners than acetylene gas burners.

What I claim as my invention is:—

1. In an electrically-igniting burner having a metallic standard and opposing jets, 25 a clip central between said jets, said clip expanding against the walls of the opening between the individual jets and being formed with portions reaching down and in electrical contact with said standard, in combination with a coil located in one of 30 said jets and connected at one end to said clip.

2. In an electrically-igniting burner having a metallic standard and opposing jets, a 35 clip central between said jets, said clip expanding against the walls of the opening between the individual jets and being

formed with portions reaching down and in electrical contact with said standard, in combination with a coil located in one of said jets and connected at one end to said clip, and a second clip having arms embracing said jet the other end of said coil being connected to said second clip.

3. In an electrically-igniting burner having a metallic standard and opposing jets, a clip central between said jets, said clip expanding against the walls of the opening between the individual jets and being formed with portions reaching down and in 45 electrical contact with said standard, in combination with a coil located in one of said jets and connected at one end to said clip, and a second clip having arms embracing said jet the other end of said coil being connected to said second clip, and means of electrically insulating the second clip from the first.

4. In a divided jet burner having a metallic base, a lighting means comprising a 60 clip circularly embracing the burner by outward pressure within the circular recess between the jets, said clip being also provided with extensions reaching downward to, fitted to and fastened and connected electrically to 65 the metal base piece of the burner.

5. In a divided jet burner, a central clip internally embracing the jet-piece above and in electrical contact with the metal jet-holder-base-piece below.

HERBERT B. STEELE.
